UNITED STATES PATENT OFFICE.

GEORGE W. DONNING, OF EAST ORANGE, NEW JERSEY, ASSIGNOR OF ONE-HALF TO HARRY T. AMBROSE, OF ORANGE, NEW JERSEY.

TYPE-WRITER-ACTUATING MECHANISM.

SPECIFICATION forming part of Letters Patent No. 745,095, dated November 24, 1903.

Application filed May 2, 1902. Serial No. 105,548. (No model.)

To all whom it may concern:

Be it known that I, GEORGE W. DONNING, a citizen of the United States, residing at East Orange, in the county of Essex and State of New Jersey, have invented certain new and useful Improvements in Type-Writer-Actuating Mechanism; and I do hereby declare the following to be a full, clear, and exact description of the invention, such as will enable others skilled in the art to which it appertains to make and use the same.

The object of my invention is to provide coöperating mechanisms for writing-machines, the several mechanisms being arranged to operate successively. In this construction a light touch of the key element is sufficient to start the first mechanism in operation, after which the remaining mechanisms come successively into operation, where-by a train of movement results after the necessary impetus is effected upon the said first mechanism.

A further object is to provide means for producing a clear, accurate, and exact impression.

To these ends my invention consists in the constructions, combinations, and arrangements hereinafter described and claimed.

In the accompanying drawings, forming a part of this application, and in which similar reference-symbols indicate corresponding parts in the several views, Figure 1 is a detail perspective view showing particularly a carriage for a flat-platen type-writer upon which is carried the type-bars and actuating mechanism, ribbon-spools and actuating mechanism, ribbon-guides and actuating mechanism, and transverse escapement mechanism. Fig. 2 is a detail sectional elevation. Fig. 3 is a sectional elevation showing more particularly the type-head actuating and releasing mechanism. Figs. 4 and 5 are detail views showing in dotted lines the position of the cams forming a part of the type-head-actuating mechanism. Fig. 6 is a sectional elevation of the type-bar and its type-head-actuating mechanism, the various positions of the type-bar and its type-head-actuating mechanism when being actuated being shown in dotted lines. Fig. 7 is a sectional elevation of the type-bar and key

member and the levers and links connecting therewith. Fig. 8 is a detail view of the type-bar, partly broken away to show the housing at the upper portion of the type-bar, and the type-head being partly broken away to show the connection between it and its locking-pawl. Fig. 9 is a detail view of the type-head. Fig. 10 is a side elevation, on a reduced scale, showing a letter and line finder mechanism. Fig. 11 is a bottom plan view showing the mechanism of Fig. 10. Fig. 12 is a detail perspective view showing the arrangement of parts for operating the ribbon-spool, and Fig. 13 is a detail sectional elevation showing such operating parts.

Referring to the drawings in detail, A indicates the carriage of a writing-machine.

B indicates one of the ribbon-spools, at least one such spool being provided at each side of the carriage and said spools arranged to act alternately as feeding and receiving spools. Rock-arms N, preferably positioned adjacent each side of the frame, are maintained by springs N' in position to turn on a rod d¹. A universal bar H is carried by the free ends of said rock-arms, and an arm H' extends from each rock-arm. A link H² is pivotally connected at its respective ends to the arm H' and to a lever H³, which latter is constructed to actuate the ribbon-spool through a pawl-and-ratchet mechanism H⁴, which need not be further described, as it is claimed in my copending application, Serial No. 107,471, and constitutes no part of my invention as claimed in this application.

Loosely mounted upon the universal bar H is a lever P, which acts upon depression of said universal bar to lower the ribbon-guide B³ through the intermediary of bell-crank levers P' P³ and their connecting-link P².

An arm S, mounted on the universal bar H, is pivotally connected to a lever C², arranged to actuate the transverse escapement C after the bar H has been depressed to a predetermined position, an adjustable contact-screw C³ providing means for regulating the point at which the transverse escapement will be actuated. This specific intermediary mechanism and transverse escapement need not be further referred to, since they are claimed

in my copending application, Serial No. 107,471, and constitute no part of my invention as claimed in this application.

D indicates one form of type-bar, which 5 may be of any convenient shape, but is here shown U-shaped to constitute a housing for parts carried thereon. An enlargement d on the lower portion of this bar is provided with an opening to receive a pivot or fulcrum-rod 10 for securing the bar to a guide-yoke or fulcrum-plate D², formed in the base-plate. A rock-arm d⁵ is pivoted at d⁷ in a bearing d⁴ on the type-bar. A spring d⁹ is connected at its respective ends to the rock-arm d⁵ and to a pawl 15 d¹⁰ for returning said parts to their normal position. A type-head-actuating link d¹¹ has its lower end pivotally mounted at d¹² on a projecting portion d^{13a} of the rock-arm d⁵ and is pivotally connected at its upper end with 20 an extension d¹⁶ on the type-head d¹⁴, which is pivotally secured to the type-bar D.

The rock-arm d⁵ is provided with a tailpiece 25 for engaging a type-head shifter E, and said tailpiece may be formed of inclined parts d^{5a} d¹⁵, as shown.

The pawl d¹⁰ is pivoted to the type-bar at d¹⁹ and is adapted to engage teeth d¹⁸ on the type-head d¹⁴. As shown in Fig. 8, the pawl d¹⁰ is so arranged that when in engagement 30 with the teeth of the type-head it will permit adjustment of the type-head in a direction contrary to the movement of a clock's hands, but will lock said type-head against opposite movement.

35 The type-head is provided with suitable type-holding means, such as sockets d²², and may have its semicircular face split, as at d²³, to permit bending of the sockets for alining the type. While I have shown the type-head designed to carry three characters, it 40 is obvious that a greater or less number of characters could be provided, as desired.

The guide-yokes D² may be formed in the base-plate, as shown, or may consist of a separate piece for each type-bar.

An important distinction of my guide-yoke 50 over the usual straight pivot or cone-bearing is that it provides with a minimum of friction a broad guiding-surface for the type-bar throughout its entire arc of movement, and by causing the sides D⁴ of the guide-yoke to bear against the type-bar in a manner inappreciable as presenting resistance lateral play of the type-bar will be obviated. 55 A rod D^{2xx} may be inserted in the groove D^{2x} for pivotally supporting said type-bars. A spring d²⁵, attached to the type-bar at d²⁴ and to a pin d²⁶ on the frame, acts to return the type-bar to its normal upright position after 60 being operated to print.

Properly to adjust the type-head d¹⁴ for printing any desired one of the characters carried thereby I provide a shifter-bar E, preferably extending in the arc of a circle 65 from one side to the other of the carriage and supported by a plurality of hangers e³. The hangers e³ have their upper ends e⁴ se-

cured to arms e⁵, provided at their rear ends with vertical pieces e⁶, which are pivotally connected to parallel arms f and f². The 70 arm f rests upon a transverse rod d¹¹ and has a projecting end f⁶, with which connects a spring f⁷, having its other end attached at f⁸ to the arm f² for holding said latter arm against the transverse rod d³⁹, as shown. A 75 yoke-piece f⁵, carrying a key member F, is pivotally connected at f³ and f⁴, respectively, with two parallel arms f^a and f^{2a}, which are supported on the transverse rods d⁴¹ and d³⁹ and connected by a spring f^{7a}. Extending 80 across the carriages is a shaft f⁹, which carries cams f¹⁰, arranged to engage bearing-pieces e⁷ on the arms e⁵. A lug f¹⁶, secured on said shaft, engages the yoke-piece f⁵, as clearly shown in Fig. 6. 85

When the key member F is depressed, the downward motion of the yoke-piece f⁵ and its engaged lug f¹⁶ causes the shaft f⁹ to turn, raising the shifter-bar E through the engagement of cams f¹⁰ with their bearing-pieces e⁷. 90 A second yoke-piece f¹⁴, carrying a key member F², is provided for raising the shifter-bar E sufficiently to actuate the type-head d¹⁴ and bring its third character into proper printing position. Thus when the shifter E is raised 95 it will lie in front of the part d^{5a}, and a downward movement of the type-bar D for printing will bring the front face of the part d^{5a} in contact with the shifter and cause it to ride up over the same, thereby producing a 100 trigger action to raise the rock-arm d⁵ and adjust the type-head d¹⁴. The portion d¹⁵ is so shaped that during the return of the type-bar to its normal upright position it can ride over the shifter-bar E, even when the latter 105 has been raised for co-operation with a subsequently-actuated type-bar. Yoke-piece f¹⁴ is supported on parallel bars f¹¹ and f¹², which are held against their bearings d⁴¹ and d³⁹ by a spring f¹³, and a lug f¹⁵ on the shaft f⁹ engages with said yoke-piece, all in a manner similar to the connections of the previously-described yoke-piece f⁵.

For actuating the type-bar D, I provide a link d²⁷, pivoted to the toe d² of the type-bar at 115 d³ and having its other end pivoted at d²⁸ to a sublever d³⁰, which is fulcrumed at d³⁰ on the base. A link d³³ is pivotally connected at d³² and d³⁵ with said sublever and a key member D³, respectively. Said link is preferably provided with adjusting means, such as a turnbuckle d³⁴. The key member is pivotally supported at d³³ and d⁴⁰ with two parallel arms d³⁶ and d³⁷, respectively. Said 120 parallel arms bear on the transverse rods d³⁹ d⁴¹ and are connected by a spring d⁴³, as clearly shown in Fig. 7. This construction forms the subject-matter of a divisional application hereof filed this date and need not be further described herein. 125

It will be noted that upon depressing the key member D³ the early motion of the rock-ing lever d²⁹ will tend to move the pivot d²⁸ of link d²⁷ in a path approximately perpendicu-

lar to the length of said link. This motion will act to swing the link d^{27} about its pivotal connection d^3 to the type-bar without materially rocking said type-bar, thus moving the link d^{27} and lever d^{29} from their initial locked position, in which their axis lay substantially in a common straight line. Upon further depression of key member D^3 the rocking lever d^{29} acts to move the pivot d^{28} of link d^{27} in an arc (about pivot d^{30}) which more and more approaches a path parallel to the axis of said link d^{27} , and thereby causes a progressive acceleration in the motion of the type-bar D about its pivot D^{28} . During such movement of the type-bar D its rock-arm d^5 engages the rod E and adjusts the type-head d^{14} . As the key member D^3 continues to descend the link d^{27} engages and carries down the universal bar H, and thereby starts the operation of the ribbon-guide and ribbon-spool and then starts the operation of the transverse escapement. Thus the pivots d^3 , d^{28} , and d^{30} (see especially Fig. 7) are so arranged that the type-bar D is locked against any rebound from its upright position and can be rocked from such position only by depressing the key member D^3 . The link d^{27} and adjacent end of the lever d^{29} constitute a toggle-joint, and, as shown, the pivot d^3 is located slightly below a straight line passing through the centers of pivots d^{28} and d^{30} of said toggle. Any force applied to the type-bar D to rock it from its normal upright position will be transmitted through the pivot d^3 to the link d^{27} , and obviously the effectiveness of that component of such force which tends to bend the toggle varies directly with the perpendicular distance from the pivot d^3 to a right line passed through the centers of pivots d^{28} and d^{30} . In the construction shown this perpendicular distance is made so small that the force is expended mainly in causing pressure on the pivots d^3 , d^{28} , and d^{30} and is ineffective to bend the toggle against the friction engendered by such pressure. Of course by locating all three pivotal points d^3 , d^{28} , and d^{30} in a right line tangent to the path of the point d^3 the entire force transmitted through the point d^3 to link d^{27} would be expended in causing pressure on said pivots, or, again, by locating the pivot d^3 above the right line passing through the centers of pivots d^{28} and d^{30} the force transmitted through the pivot d^3 to the link d^{27} would tend to maintain the toggle in its locked position.

Disposed to the rear of the type-bars and preferably in alinement with the type-heads is a type-head releasing or unlocking rod or bar G, against which the downward-extending portion d^{21} of the pawl d^{10} contacts upon the return of the type-bar to its normal upright position. It is to be understood that when the portion d^{21} of the pawl d^{10} contacts with this releasing or unlocking bar G the tooth d^{20} of the pawl is disengaged from the teeth d^{18} of the type-head, permitting the type-head to resume its normal position, such as that shown in Fig. 8.

By maintaining the pawl d^{10} in contact with the releasing-rod G normally it is held out of engagement with the head, so that the same is normally free of movement, and it is not until the type-head is started on its downward course and the pawl leaves the releasing-bar G that it again engages the teeth d^{18} in the type-head to hold the same in the right position during the descent of the type-bar to print.

The rod or bar G is preferably supported on standards g , which are disposed on the base-plate. The upper portion of these standards g are provided with a protecting-head g^2 , provided with an opening g^3 . The lower portion is provided with a foot g^4 , through which penetrates a securing-screw g^5 . Depending preferably from near the central portion of the standard g at the rear is a brace g^6 , having a foot g^7 , through which penetrates a screw g^8 . These two feet g^4 and g^7 are preferably secured to the fulcrum-plate D^2 over the slots D^{2888} to hold in place therein the rods, &c. To remove these rods, it is not necessary to take off the standards, as a rod may be pushed through the slot to force the other forward and out. Upon the outer edge of the standard near the center is a projecting bridge e , in which is held and guided the rod E.

The parts—such as the type-bars, connecting-links, parallel links, and arms—are all constructed to facilitate assembling and replacing. The parallel arms $f^2 f^{11} f^{12}$, for instance, are cut out where they contact with the rods $d^{29} d^{41}$, as shown in Figs. 3 and 6, so that they may be removed without disturbing other parts. The springs $f^7 f^{13}$, connecting therewith, serve to hold them in place and at the same time to take up any lost motion that may exist.

A point to be noted in connection with the type-head as differentiating it from those in common use is that in all shifting multiple type-heads the type-head is not locked in proper printing position relative to its bar while going down and locked coming up, so that should there be interference between two of the type-heads the type-head will be shifted on the descending type-bar—that is, if the interference takes place before the platen is reached—while the type-head on the ascending type-bar is securely locked. Such arrangement is obviously objectionable in the presentation of a thoroughly-operative device. In the type-bar of the present invention the head is positively and securely locked when the type-bar is descending, so that the operator is sure of the correct character, and should two of the type-heads interfere the type-head on the returning type-bar, by reason of the construction of the type-head, unlocks and moves or rocks out of the path of the descending type-head, and just before the type-head resumes its normal position the locking device contacts with the type-head releaser or abutting surface and causes the type-head to swing back to its normal position.

In Figs. 10 and 11 I have illustrated a novel form of combined line and letter finder to co-operate with the writing mechanism. This device is preferably disposed on the under side of the base or fulcrum plate D^2 and is operated by a key I , preferably formed of three members i , i^2 , and i^3 , the member i^2 being fulcrumed at i^3 on the side plate A and the member i^3 provided at its lower extending end i^5 with a pivot i^6 , with which is connected an arm or lever J , fulcrumed at j on the fulcrum-plate D^2 . The lever or arm J beyond the fulcrum-point j has a perforation at j^2 , in which is secured a spring j^3 , connecting at its other end with a pin j^4 on the fulcrum-plate. Pivoted upon the end of the lever or arm J is a second arm K approximately of the outline shown in Fig. 11 to afford a cam-bearing surface k , engaging a headed screw k^2 , serving to hold the arm K against the under side of the fulcrum-plate. A line and letter finder arm L is pivotally secured at k^3 to the arm K and provided with a foot l , having an incut l^2 and a straight edge l^3 . On the end of arm K is secured a spring k^3 , which serves to hold the line and letter finder arm L normally in proper horizontal position above the platen out of contact with the work in the machine. A guide M , secured to the base-plate D^2 , carries an inclined portion M' , which is arranged to engage the upper surface of the arm L and guide said arm downward during its movement around to the printing-point. The cut-out portion l^2 of the foot l permits the operator to see the last printed letter. The corner l^3 is to point to the center of a letter to be inserted or struck. Now when the key I is depressed the arm J is moved in the direction indicated by the arrow, Fig. 11. This causes the curved arm K to be moved against the bearing-screw k^2 , effecting withdrawal and swing of the arm L to a position under the fulcrum-plate, as indicated in dotted lines. When the arm L is swung out to a line, it contacts with the guide-piece M , and by reason of the inclined face thereof is thrust downward. This line and letter finder is of great simplicity and efficiency and insures accuracy to indicate exactly the printing-point. It is quickly drawn back to its normal position out of the area of operation when not needed. The lining-up strip or edge being projected toward the operator enables her to point the spot exactly. Where the operator has to look down and over an edge, perfect pointing is not possible, notwithstanding that the scale edge may be sharp.

Having thus described my invention, what I claim as new, and desire to secure by Letters Patent, is—

1. In a writing mechanism, the combination of type mechanism, a ribbon-feed, a ribbon-guide, a transverse escapement, a common operating means, and intermediary mechanisms constructed to actuate said type mechanism, ribbon-feed, ribbon-guide, and transverse escapement, said intermediary mechan-

isms constructed and arranged to start the operation of the type mechanism prior to the operation of said ribbon-feed and ribbon-guide, and to start the operation of the ribbon-feed and ribbon-guide prior to the operation of the transverse escapement, substantially as described. 70

2. In a writing mechanism, the combination of type mechanism, a ribbon-feed, a ribbon-guide, a transverse escapement, a common operating means, and co-operating actuating mechanisms constructed to actuate said type mechanism, ribbon-feed, ribbon-guide and transverse escapement, said co-operating actuating mechanisms constructed and arranged to start the operation of the type mechanism prior to the operation of said ribbon-feed and ribbon-guide, and to start the operation of the ribbon-feed and ribbon-guide prior to the operation of the transverse escapement, substantially as described. 80

3. In writing mechanism, the combination of a type-bar, a type-head pivotally carried thereon and provided with a plurality of type, means constructed completely to actuate said type-head toward the outset of its downward movement, means independent of the actuating means and constructed to lock said type-head upon completion of its actuation, and means constructed and arranged to operate said actuating mechanism, substantially as described. 90

4. In writing mechanism, the combination of a type-bar, a type-head pivotally carried thereon and having a plurality of type, means constructed completely to actuate the type-head toward the outset of its arc of movement, such actuating means comprising a link connected with the type-head, a rocking arm supporting said link and carrying a depending tailpiece, means independent of said actuating means and constructed to lock said type-head, and means arranged to engage said tailpiece to effect movement of the type-head, substantially as described. 100

5. In writing mechanism, the combination of a type-bar formed to constitute a housing for the parts carried thereon, a type-head pivotally carried on said type-bar and provided with a plurality of type, mechanism constructed to completely actuate the type-head toward the outset of its arc of movement, means independent of the actuating means 115 and constructed to lock said type-head upon completion of its actuation, and means constructed and arranged to operate said actuating mechanism, substantially as described. 120

6. In writing mechanism, the combination of a type-bar having its upper portion formed to constitute a housing for parts carried thereon, and its lower portion constituting bearing-surfaces, a type-head pivotally carried on said type-bar and provided with a plurality of type, mechanism constructed completely to actuate the type-head toward the outset of its arc of movement, means independent of the actuating means and constructed to lock said 130

type-head upon completion of its actuation, and means constructed and arranged to operate such actuating mechanism, substantially as described.

- 5 7. In writing mechanism, the combination of a type-bar, a type-head pivotally carried thereon and provided with a plurality of type, mechanism constructed completely to actuate the type-head toward the outset of its arc of movement, means independent of the actuating means and constructed to lock said type-head upon completion of its actuation, means constructed to effect return of the parts to normal position, and means constructed and arranged to operate such actuating mechanism, substantially as described.

8. In writing mechanism, the combination of a type-bar, a type-head pivotally carried thereon and provided with a plurality of type, mechanism constructed completely to actuate said type-head toward the outset of its arc of movement, means independent of the actuating means and constructed to lock said type-head upon completion of its actuation, means constructed to operate such actuating mechanism, and means constructed and arranged to effect accelerated return of the parts to normal position, substantially as described.

9. In writing mechanism, the combination of a type-bar, a type-head pivotally carried thereon and provided with type, guiding and supporting means for said type-bar, mechanism constructed completely to actuate the type-head toward the outset of its arc of movement, means independent of the actuating means and constructed to lock said type-head upon completion of its actuation, and means constructed and arranged to operate such actuating mechanism, substantially as described.

10. In writing mechanism, the combination of a type-bar, a type-head pivotally carried thereon and provided with type, a guide-yoke arranged to support and guide said type-bar, mechanism constructed completely to actuate the type-head toward the outset of its arc of movement, means independent of the actuating means and constructed to lock said type-head upon completion of its actuation, and means constructed and arranged to operate such actuating mechanism, substantially as described.

11. In writing mechanism, the combination of a type-bar, a type-head pivotally carried thereon and provided with type, mechanism constructed completely to actuate the type-head toward the outset of its downward stroke, means independent of the actuating means and constructed to lock said type-head upon completion of its actuation, means constructed to operate such actuating mechanism, and key mechanism constructed and arranged to effect operation of the type-bar, substantially as described.

12. In writing mechanism, the combination of a type-bar, a type-head pivotally carried thereon and provided with type, mechanism

constructed and arranged completely to actuate the type-head toward the outset of its arc of movement, means independent of the actuating means and constructed to lock said type-head upon completion of its actuation, means constructed to operate such actuating mechanism, key mechanism arranged to effect operation of said type-bar, said key mechanism comprising a key member, a link pivotally connected thereto, a rocking sublever connected with said link, and a second link connecting the rocking sublever and the type-bar, substantially as described.

13. In writing mechanism, the combination of a type-bar, a type-head pivotally carried thereon and provided with type, mechanism constructed completely to actuate the type-head toward the outset of its arc of movement, means independent of the actuating means and constructed to lock said type-head upon completion of its actuation, means constructed to operate such actuating mechanism, key mechanism arranged to effect operation of the type-bar, said key mechanism comprising a key member, a sublever, a link connecting said key member and sublever and provided with adjusting means, and a link connecting said sublever and type-bar, substantially as described.

14. In writing mechanism, the combination of a type-bar, a type-head pivotally carried thereon and provided with a plurality of type, and constituted of a segment with an outer, curved periphery, mechanism constructed to completely actuate said type-head toward the outset of its arc of movement, means independent of the actuating means and constructed to lock said type-head upon completion of its actuation, and means constructed and arranged to operate such actuating mechanism, substantially as described.

15. In writing mechanism, the combination of a type-bar, a type-head pivotally carried thereon and provided with teeth, means constructed to actuate the type-head, a pawl pivotally mounted on the type-bar and adapted to engage said teeth to effect locking of the same, and means constructed to operate such locking device, substantially as described.

16. In writing mechanism, the combination of a type-bar, a type-head pivotally carried thereon and provided with teeth, a pawl pivotally carried on the type-bar and adapted to engage said teeth, a spring connected to said pawl to hold it normally in engagement with said teeth, mechanism constructed completely to actuate the type-head into locking engagement with said pawl toward the outset of its downward movement, and means constructed and arranged to operate such actuating mechanism, substantially as described.

17. In writing mechanism, the combination of a type-bar, a type-head pivotally carried thereon, a pawl pivotally carried on said type-bar and adapted normally to engage said type-head to lock the same, mechanism constructed completely to actuate the type-head into

locking engagement with said pawl toward the outset of its arc of movement, means constructed to operate such actuating mechanism, and means constructed and arranged to effect disengagement of the pawl from locking engagement with said type-head, substantially as described.

18. In writing mechanism, the combination of a type-bar, a type-head pivotally carried thereon, a pawl pivotally carried on the type-bar and adapted normally to engage the type-head to lock the same, mechanism constructed completely to actuate the type-head into locking engagement with said pawl toward the outset of its arc of movement, and an abutment-surface disposed in the path of said pawl and arranged to effect movement thereof to disengage it from locking engagement with said type-head, substantially as described.

19. In writing mechanism, the combination of a type-bar, a type-head pivotally carried thereon, mechanism constructed completely to actuate said type-head toward the outset of its arc of movement, said mechanism comprising a link connected with the type-head, a rocking arm pivotally supporting said link and provided with a depending portion, operating mechanism arranged to be engaged by said depending portion, said depending portion constructed to ride over said operating mechanism and thereby effect movement of said rocking arm and type-head, and means independent of said actuating means constructed to lock said type-head in position, substantially as described.

20. In writing mechanism, the combination of a type-bar, a type-head pivotally carried thereon, mechanism constructed completely to actuate said type-head toward the outset of its arc of movement, said mechanism comprising a link connected with the type-head, a rocking arm pivotally supporting said link and provided with a depending portion, operating mechanism arranged to be engaged by said depending portion, said depending portion constructed to ride over said operating mechanism and thereby effect movement of said rocking arm and type-head, a pawl pivotally carried on said type-bar and adapted to engage said type-head and lock the same, and a spring connecting said pawl and rocking arm to maintain said two elements in operative position, substantially as described.

21. In writing mechanism, the combination of a type-bar, a type-head pivotally carried thereon, mechanism constructed to completely actuate said type-head toward the outset of its arc of movement, said mechanism comprising a link connected with the type-head, a rocking arm pivotally supporting said link and provided with a depending portion, operating mechanism arranged to be engaged by said depending portion, said depending portion constructed to ride over said operating mechanism and thereby effect movement of said rocking arm and type-head, a pawl pivotally carried on said type-bar and adapted to

engage said type-head and lock the same, a spring connecting said pawl and rocking arm to maintain said two elements in operative position, and means arranged to actuate said pawl and remove it from locking engagement with the type-head, substantially as described.

22. In writing mechanism, the combination of a type-bar, a type-head pivotally carried thereon, mechanism constructed completely to actuate said type-head toward the outset of its arc of movement, said mechanism comprising a link connected with the type-head, a rocking arm pivotally supporting said link and provided with a depending portion, operating mechanism arranged to be engaged by said depending portion, said depending portion constructed to ride over said operating mechanism and thereby effect movement of said rocking arm and type-head, a pawl pivotally carried on said type-bar and adapted to engage said type-head and lock the same, and an abutment arranged in the path of said pawl and constructed to remove said pawl from engagement with the type-head, substantially as described.

23. In writing mechanism, the combination of a type-bar, a type-head pivotally carried thereon and provided with a plurality of type, mechanism constructed to completely actuate said type-head toward the outset of its arc of movement, means independent of the actuating means and constructed to lock said type-head upon completion of its actuation, means constructed to operate such actuating mechanism, said operating means comprising a shifting rod adjacent to the type-bar and means constructed to operate said shifting rod, substantially as described.

24. In writing mechanism, the combination of a type-bar, a type-head pivotally carried thereon and provided with a plurality of type, mechanism constructed completely to actuate said type-head toward the outset of its arc of movement, means independent of the actuating means and constructed to lock said type-head upon completion of its actuation, means constructed to operate such actuating mechanism, said operating means comprising a shifting rod adjacent to the type-bar, and shifting keys constructed and arranged to operate said shifting rod, substantially as described.

25. In writing mechanism, the combination of a type-bar, a type-head pivotally carried thereon and provided with a plurality of type, mechanism constructed completely to actuate said type-head toward the outset of its arc of movement, means independent of the actuating means and constructed to lock said type-head upon completion of its actuation, means constructed to operate such actuating mechanism, said operating means comprising a shifting rod, hangers arranged to support said shifting rod, and means constructed to effect movement of said shifting rod to varying heights or positions, substantially as described.

26. In writing mechanism, the combination of a type-bar, a type-head pivotally carried thereon and provided with a plurality of type, mechanism constructed completely to actuate said type-head toward the outset of its arc of movement, means independent of the actuating means and constructed to lock said type-head upon completion of its actuation, means constructed to operate such actuating mechanism, said operating means comprising a shifting rod, hangers arranged to support said shifting rod, and means constructed to effect movement of said shifting rod to varying heights or positions, said means comprising coöperating cams and bearing-pieces, substantially as described.

27. In writing mechanism, the combination

of a type-bar, a type-head pivotally carried thereon and provided with a plurality of type, mechanism constructed completely to actuate and lock said type-head toward the outset of its arc of movement, means constructed to operate such actuating mechanism, and a line and letter finder constructed and arranged to coöperate with the writing mechanism to indicate the position of the printing-point, substantially as described. 20 25

In testimony whereof I affix my signature in the presence of two subscribing witnesses.

GEORGE W. DONNING.
